UNITED STATES PATENT OFFICE.

WILLIAM COVINGTON WILLIAMS, OF NEW ORLEANS, LOUISIANA.

PORTABLE PROPELLING DEVICE.

1,379,889.

Specification of Letters Patent. Patented May 31, 1921.

Application filed May 25, 1918. Serial No. 236,662.

To all whom it may concern:

Be it known that I, WILLIAM COVINGTON WILLIAMS, a citizen of the United States, residing at New Orleans, in the parish of Orleans, State of Louisiana, have invented certain new and useful Improvements in Portable Propelling Devices, of which the following is a specification.

This invention relates to the subject of marine propulsion and has particular reference to a novel improvement in manually operated motor devices for propelling small boats and the like.

One of the objects of the invention is to provide a device which may be constructed of readily available materials, such for instance as sections of pipe which are capable of being readily fitted together to form the desired frame work of the device, while at the same time providing a thoroughly practical, reliable, and substantial construction.

Another object of the invention is to provide a propelling device which may be adjustably fitted to the stern of a boat in such a manner that the depth at which the propeller operates may be regulated within certain reasonable limits, whereby the device may be successfully used on light draft boats designed and intended to operate in shallow waters.

A further object of the invention is to provide a novel mounting for the propeller unit of the device which receives its power from a substantially perpendicular shaft carrying a fly wheel directly thereon, which materially improves the ease with which the propeller unit may be operated. That is to say, it is proposed to provide a construction which permits of delivering a maximum amount of power and speed to the propeller unit with a minimum expenditure of driving effort, thereby increasing the ease with which the boat may be propelled.

With the above and other objects in view which will more readily appear as the nature of the invention is better understood, the same consists in the novel construction, combination and arrangement of parts hereinafter more fully described, illustrated and claimed.

A practical embodiment of the invention is shown in the accompanying drawings, in which:—

Figure 1 is a side elevation of my entire device fitted to the stern of a boat.

Fig. 2 is a top plan view with the fly wheel removed.

Fig. 3 is a rear elevation of a boat having the present device applied thereto.

Fig. 4 is a detail side elevation of a modified type of driving unit.

Similar reference characters designate corresponding parts throughout the several figures of the drawings.

Referring to the accompanying drawings which illustrate a practical embodiment of the invention it will be observed that the device essentially comprises an attaching bracket for affixing the same to the stern of a boat, a driving unit adapted to be manually actuated by an occupant of the boat, and a propeller unit which is adapted to be manipulated also by an occupant of the boat to steer the same, and the said propeller unit having operative connections with the driving unit.

Referring now to the particular structural elements which carry the foregoing combination of units and combination of parts into effect, it may be observed from Fig. 1, 80 that the driving unit includes in its organization a horizontal shaft X which extends through a hollow iron casing or pipe which projects over the seat at the rear or stern of the boat. The said shaft X carries the 85 relatively large bevel gear A at its rear end and the pinion B at its forward end which engages with the manually actuated bevel gear E of the driving unit.

The rear end of the pipe or casing which 90 houses the main driving shaft X is supported by a clamp or bracket J for attaching the device to the stern of the boat, and is connected therewith by means of a relatively stiff swing joint K. By reason of 95 the type of bracket disclosed it will be apparent that the same may be fitted in any desired position to the stern of the boat to give the desired working depth for the propeller unit, and furthermore the relatively 100 stiff swing joint K conveniently provides for adjusting the driving instrumentalities for the propeller unit in a perpendicular position.

The relatively large bevel gear A carried 105 by the rear end of the main driving shaft X of the driving unit meshes with the bevel pinion C carried by the relatively perpendicular shaft D which runs down partly inclosed as shown, and terminates at F, a 110

small bevel pinion working into a larger bevel gear G at end of propeller shaft H. At upper end of perpendicular shaft D is fly wheel I.

5 The horizontal shaft X and perpendicular shaft D both work on ball bearings at ends, as do also propeller shaft H and the shaft of bevel gear E. All ball bearings are indicated by letter L.

10 M is coupling on perpendicular shaft for convenience in detaching lower end when necessary.

In Fig. 3 N, N are arms of the steering attachment. O, is attached to these arms 15 extending out, up and across stern of boat, as shown by R in Fig. 2.

In Fig. 2 the joint Q is swinging but stiff and by moving steering arm R the propeller is moved in either direction, as per dotted 20 lines, and steers boat.

The machine is operated either by crank, as shown in Figs. 1 and 2, or by levers, as shown in Fig. 4. In the latter case the two levers S are pivotally attached as at S' to 25 the support T shown in full lines in Fig. 4 and indicated by dotted lines T on Fig. 1 and in the former case the axle of bevel gear E supplied with short crank arms, etc. as shown.

30 Fig. 2 shows attachment for swinging propeller and down view of arm P extending over seat of boat.

The arm P is detachable at joint U for purpose of packing and the whole device 35 can then be packed into a valise like box and carried with ease.

The object of the device is to attach to stern of any light skiff and to propel it as follows:—

40 The operator sitting in stern of boat with arm of motor under his arm, turns crank or works levers as case may be. This revolves large bevel gear E on pinion B, multiplying speed at bevel gear A, which in turn 45 works upon pinion C, on perpendicular shaft D, at bottom and of which pinion F works into larger bevel gear G.

From the foregoing it will be apparent 50 that the present device provides a simple means for propelling small light boats, and by reason of its relatively light and portable nature may be conveniently utilized where it is difficult to obtain other means of mechanical propulsion.

55 Briefly summarizing the invention it will be observed that the same essentially comprises an attaching bracket adapted to be secured to the stern of the boat and having a transverse pivot K formed by a four way 60 pipe fitting (Fig. 2) and through which the driving shaft X extends. This fitting K is connected with another four way fitting K' whose members K² receive the base portion of a relatively U-shaped frame consisting of 65 the vertical part K³ and arms K⁴ having at

their outer ends the T-fittings K⁵. These T-fittings K⁵ constitute guides and bearings for drive shaft D which carries the propeller I at one end thereof and the pinion F at the other. The lower T-fitting K⁵ cooperates with the relatively short tubular element K⁶ which constitutes a part of the swiveled joint Q that also includes the four way fitting K⁷, the portions K⁸ of which connect with the steering arms N—N 70 through suitable intermediate fittings K⁹. The lower part of the fitting K⁷ carries the tubular element K⁹ which in turn supports an angular propeller supporting bracket K¹⁰ having the T-fitting K¹¹ at its lower end for receiving the propeller shaft H which carries the propeller and the gear wheel G that meshes with the pinion F on the end of the drive shaft D. By reason of the relatively swiveled connection of the fitting K⁸ with 80 the part K⁶ which constitute the joint Q it will be apparent that the propeller supporting bracket K¹⁰ may be shifted through an arc of a circle whose axis is coincident with the drive shaft. Thus, the propeller may be shifted independently of whether the drive shaft D is in operation or not when the steering arm R is moved by the occupant 85 of the boat.

Without further description it is thought 90 that the features and advantages of the invention will be readily understood, and it will of course be understood that changes in the form, proportion and minor details of construction may be resorted to without departing from the spirit of the invention or 95 scope of the appended claims.

I claim:

1. A portable propelling device of the class described, including an attaching bracket, a substantially U-shaped frame having its intermediate portion pivotally attached to said bracket, a propeller supporting bracket including relatively horizontal and vertical tubular portions, said vertical 105 portion being attached to one end of the U-shaped frame, a fly-wheel carrying shaft journaled in the outer ends of the arms of the U-shaped frame and extending through the vertical portion of the propeller supporting bracket, and a propeller carrying shaft journaled in the horizontal tubular portion of the propeller supporting bracket and operatively connected with the fly-wheel carrying shaft. 110

2. A portable propelling device of the class described including an attaching bracket, a substantially U-shaped frame having its intermediate portion pivotally secured to said bracket, a propeller unit including journal portions disposed at right angles to each other, one of said journal portions having a swiveled connection with one of the arms of the U-shaped frame, a fly-wheel carrying shaft journaled in the outer 120 125 130 135 140 145 150 155 160 165 170 175 180 185 190 195 200 205 210 215 220 225 230 235 240 245 250 255 260 265 270 275 280 285 290 295 300 305 310 315 320 325 330 335 ends of the arms of the U-shaped frame and also in the journal member of the propeller unit, and a propeller carrying shaft mounted in the other journal portion of the propeller unit and having an operative engagement with the fly-wheel carrying shaft.

3. A portable propelling device of the class described including an attaching bracket, a substantially U-shaped frame secured at its intermediate portion to said bracket, a dirigible propeller unit carried by the lower end of the U-shaped frame, said dirigible propeller unit including a bracket having a portion swiveled to the lower end 15 of the U-shaped frame and also having a

propeller shaft carrying portion disposed at right angles thereto, a fly-wheel carrying shaft journaled in the ends of the arms of the said frame and also in the portion of the propeller bracket which connects with said 20 frame, and a propeller carrying shaft carried by the portion of the propeller bracket at right angles to the said portion thereof which connects with the frame and operatively connected with the fly-wheel carrying 25 shaft.

WILLIAM COVINGTON WILLIAMS.
